[57] ABSTRACT

A closure having a cap for the neck of a container, for medicines, such as pills or the like, having a central socket and an entry aperture connecting the socket in communication with the interior of the container and having a removal aperture connecting the socket in communication with the exterior air space. A spherical closure ball rotatably retained in the socket so it is universally rotatable in all directions and having a depression in one surface portion thereof of a size to receive a single dose of the contents of the container and being successively rotatable into registration with the entry aperture to receive a single dose from the container, and into registration with the removal aperture for removal of the single dose from the container, the depression in the ball also being rotatable to a multiplicity of other positions in the socket where it is covered by the housing and prevents removal of the container contents.

SAFETY CLOSURE FOR A CONTAINER

The invention relates to a safety closure for a container, particularly, but not exclusively a container for medicines, which will prevent inadvertent removal of the contents, and especially the removal of medicines by children.

Up to the present safety closures for this purpose have been made that the opening thereof requires a certain dexterity. Such closure have the disadvantage that the entire contents of the container can be removed if a child accidentally contrives to open the closure.

It is the basic object of the invention to avoid this disadvantage and to produce a safety closure such that by the application of a certain dexterity or opening procedure only one dose unit can be removed at any one time, so that the possible damage is slight if a child accidentally effects a removal.

According to the invention a safety closure for a container comprising a closure housing having an entry aperture communicating with the container space, a removal aperture communicating with atmosphere, a socket connecting the two apertures and carrying a closure ball so that the ball is rotatable in all directions therein, the surface of the ball being formed with a depression for the reception of a single dose of the contents of the container whereby on turning the ball the depression can be brought successively to the entry aperture and to the removal aperture, the arrangement being such that a plurality of other positions of the ball in the socket the depression is covered by the housing, and an indication mark on the ball and which is visible at the removal aperture when the depression is located at the entry aperture, the part of the ball exposed at the removal aperture being accessible for manual turning.

Protrusions are preferably disposed near the edge of the removal aperture and which protrude so far beyond the exposed part of the ball that this cannot be rolled on a flat surface, and between which a finger can be inserted in order to turn the ball.

The invention will now be illustrated with reference to the accompanying drawings in which:

FIG. 1 is a plan view on a safety closure, and

FIG. 2 is a section along the line II — II of FIG. 1.

The safety closure illustrated in the drawings has a closure housing 1 with a funnel-shaped entry aperture 2 and a removal aperture 3. The housing 1 is provided on the side carrying the entry aperture 2 with an annular channel 4 which engages an annular lip 5 on the outer end of the container 6. The entry aperture 2 communicates with the internal space 7 of the container 6, while the removal aperture 3 is open to atmosphere.

The housing 1 is formed with a socket 8 which communicates with the apertures 2 and 3 and which carries a closure ball 9. The ball 9 is mounted in the socket 8 so as to be freely rotatable in all directions therein.

The surface of the ball 9 is formed with a depression 10 which serves for the reception of a single dose, (e.g., a tablet or a pill) of the contents of the container 6. In the position of the ball 9 illustrated in FIG. 2 the depression 10 is positioned at the entry aperture 2. By turning the ball 9 the depression 10 can be brought into the zone of the removal aperture 3. In a great number of other positions of the ball 9 the depression 10 is covered by the surface 11 of the housing surrounding the socket 8. The surface 11 is slightly relieved from the

ball 9, so that the surface only makes contact with two residual spherical zones 12 and 13 of the surface 11 in order to keep the friction low. The ball 9 is provided with a marking groove 14 which is visible at the removal aperture 3 when the ball 9 is in the position illustrated in which the depression 10 coincides with the entry aperture 2. At the edge of the removal aperture 3, two protrusions 15 and 16 are disposed opposite to one another and extend so far beyond the exposed part of the ball 9 that this cannot be rolled on a flat surface. A finger of one hand can however penetrate between the protrusions 15 and 16 in order to turn the ball 9.

The housing 1 is made from an elastic plastics material, the diameter of the removal aperture 3 being only slightly smaller than the diameter of the ball 9, and the wall of the part of the housing bounding the removal aperture 3 is slotted at 17 and made relatively thin, so that when the closure is manufactured the ball 9 can be pressed through the removal aperture 3 into the socket 8, the removal aperture 3 being temporarily stretched in so doing.

If the seal provided by the partial contacting of the ball 9 on the wall of the socket 8 is not sufficient for any particular purpose, it is possible for a closing cap (not shown) to be provided, which can be removably pushed or screwed onto the housing 1.

In order to take one dose, for example one tablet or pill, from the container 6, the ball 9 is brought into the position illustrated in FIGS. 1 and 2 and the container is inverted so that the closure is at the bottom. Thereby a tablet or pill held in the container will pass into the depression 10. The ball 9 is then turned until the depression 10 arrives at the removal aperture, so that the tablet or pill falls out. Obviously, after the ball has been turned so far that the pill 16 is held by the wall of the socket 8, the container can also be held obliquely or with the closure upwards. Before the removal of a further pill or tablet, the ball has thus to be again turned so that the marking groove 14 is concentric with the removal aperture 3, when the depression 10 again locates on the entry aperture 2. Since the marking ring constituted by the groove 14 is comparatively large, a part of this is visible in the removal aperture in many positions of the ball, so that it is easy to see how the ball should be turned. To turn the ball one finger of one hand is pushed between the protrusions 15 and 16.

Since the container must be held with the closure downwards and with the ball in the position illustrated in FIG. 2 for a tablet or pill to pass into the depression 10, and since the tablet or pill can only be removed if the ball is sufficiently turned in this attitude of the container before the container is again held with the closure upwards, and since this tablet or pill is only removable when the ball has been further turned into the removal position, the probability that a small child can remove a tablet or pill is very small. If, exceptionally, a small child does effect the removal, it is only a question of a single tablet or pill, which normally does not constitute a serious danger. The protrusions 15 and 16 prevent a small child moving the container on a surface with the closure downwards and so rolling the ball, when under some circumstances some tablets or pills might be removed if the ball should thereby be so turned that the depression 10 repeatedly arrives at the entry aperture and thereafter at the outlet aperture.

Thus the safety closure described offers considerable security against inadvertent removal of an undesired high dose of a medicine contained in the holder.

It will be appreciated that the housing 1 can also be constituted in one piece with the container, in which case the container is filled through the apertures 3 and 2 before the insertion of the ball.

The safety closure on a container described is especially suitable for the removal of tablets, pill, lozenges, but can also be used for example for granulates or powder. The arrangement shown in the drawings ensures that powders will not increase the sliding friction of the ball too much. With granulates or powder the closure serves simultaneously as a device to meter the dosage.

What I claim is:

1. A safety closure for a container comprising a closure housing having an entry aperture communicating with the container space, a removal aperture communicating with atmosphere, a socket connecting the two apertures and carrying a ball rotatable in all directions therein, a depression formed in the surface of the ball for the reception of a single dose of the contents of the container whereby on turning the ball the depression can be brought successively to the entry aperture and to the removal aperture, the arrangement being such that in a plurality of other positions of the ball in the socket the depression is covered by the housing, an in-

dication mark on the ball which is visible at the removal aperture when the depression is located at the entry aperture, the part of the ball exposed at the removal aperture being accessible for manual turning, and protrusions on the housing disposed near the removal aperture which extend so far beyond the exposed part of the ball that the ball cannot be rolled on a flat surface, but between which a finger can be inserted in order to turn the ball.

10 2. A safety closure as claimed in claim 1, wherein the housing is made from an elastic material and the ball is inserted through the removal aperture into the socket by temporarily stretching the edge of the aperture.

15 3. A safety closure as claimed in claim 1 wherein the indicating mark is an inscribed circle which runs close to the edge of the removal aperture when the depression is located at the entry aperture.

4. A safety closure as claimed in claim 1 and including an airtight and detachable cap which can be placed 20 on the closure housing to seal the removal aperture.

5. A safety closure as claimed in claim 1, including means for securing the closure housing in an airtight and detachable manner to the container.

25 6. A safety closure as claimed in claim 1, wherein the closure housing is constituted in one piece with the container.
